APPROACH HORIZON

Arthur A. Collins and Rolf W. Wollan,
Cedar Rapids, Iowa

Application August 4, 1951, Serial No. 16,164

Term of patent 14 years

(Cl. D52—1)

To all whom it may concern:

Be it known that we, Arthur A. Collins and Rolf W. Wollan, citizens of the United States, residing at Cedar Rapids, Linn County, State of Iowa, have invented a new, original, and ornamental Design for an Approach Horizon, of which the following is a specification, reference being had to the accompanying drawing, forming a part hereof.

Figure 1 is a front view of an approach horizon showing our new design.

Figure 2 is a perspective view of our approach horizon.

The characteristic features of the design reside in the full line portions.

We claim:

The ornamental design for an approach horizon, as shown and described.

ARTHUR A. COLLINS.
ROLF W. WOLLAN.
